G. S. Malcolm

BY *Aug. J. L. D.* ATTORNEY

UNITED STATES PATENT OFFICE

GEORGE S. MALCOLM, OF AUBURN, CALIFORNIA

DISPLAY CARD HOLDER

Application filed March 29, 1932. Serial No. 601,754.

This invention relates to card holders for store shelves and particularly represents improvements over the structure shown in my co-pending application for patent, Serial No. 583,443, filed December 28, 1931.

The card holding member of the previous application and the necessary spring control means were so mounted and arranged that the holding screws could only be placed at 10 definitely fixed points, according to the judgment of the manufacturer rather than according to the needs of any individual user. Also, this construction necessitated a number of hand operations in the manufacture and 15 assembly of the device so that the cost of the same was relatively high.

The principal object of my present invention is to avoid the objectionable features of the previous device while retaining all its 20 advantages by arranging the card holding strip and spring mounting means so that the spring units are initially separate from the holder itself, and so that it is easy to make these units and the holding members on a 25 mass production basis without much, if any, hand work being necessary, thus reducing manufacturing costs. Also said spring and mounting units are now so arranged that they can be disposed along the card holding 30 strip in such spaced relation as the needs of any individual shelf installation may require.

These objects I accomplish by means of 35 such structure and relative arrangements of parts as will fully appear by a perusal of the following specification and claims.

In the drawing similar characters of reference indicate corresponding parts in the 40 several views:

Fig. 1 is a fragmentary perspective view of a store shelf arrangement showing my improved price card holder mounted in connection therewith.

Fig. 2 is an enlarged cross section of the

holder as mounted on a shelf and taken on the line 2—2 of Fig. 4.

Fig. 3 is a similar view as on the line 3—3 of Fig. 5 showing a card as being inserted or removed.

Fig. 4 is a fragmentary bottom plan view of the holder as in its normal position in connection with a shelf.

Fig. 5 is a similar view showing the holding device advanced relative to the shelf to 55 insert or remove a card.

Referring now more particularly to the characters of reference on the drawing, the numeral 1 denotes a merchandise supporting shelf on which the goods 2 of various kinds 60 are supported in segregated order as usual and as indicated in Fig. 1.

The card holder for any one shelf between the partitions 1a thereof comprises a strip 3 extending lengthwise of and under 65 the shelf adjacent its forward edge. This strip is of sheet metal and is formed with an upstanding lip 4 along the entire length of the same which extends in front of the front edge of the shelf and overlaps the 70 lower portion of said edge. The holder strip and lip may extend the full length between partitions 1a or they may be in a number of sections for each such length of shelf.

The strip also has a depending lip 5 along 75 its back edge which not only reinforces the strip against buckling but has another purpose as well, as will be seen. Cages 6 are disposed under and extend transversely of the strip at intervals. Each cage has horizontal oppositely extending base pads 7 at 80 its opposite ends, drilled to receive the necessary mounting screws 8. The forward pad and the adjacent portion of the cage underlies the strip 3, the corresponding screw projecting into the wood of the shelf through a slot 9 formed in the strip and extending transversely thereof. There are a plurality of these slots disposed in suitably spaced relation along the strip so that the cages and 85

90

their screws may be located at correspondingly different points along said strip, so that their position and the number used may be altered according to the requirements as governed by the length of the shelf section between its partitions.

The other end pad 7 of each cage bears on the shelf back of the strip so that the corresponding screw secures the cage directly to the shelf. The sides of the cage are cut away ahead of the back pad as indicated at 10, so as to permit the lip 5 passing freely through and also moving back and forth. A helical spring 11 is disposed in each cage and bears at one end against the lip 5. The other end of the spring bears against the front end of the cage and said cage is mounted on the shelf so that the spring is under compression when the lip 4 is engaged with the front edge 15 of the shelf. Said lip therefore always tends to press against the shelf with a certain pressure while at the same time it may be pulled out a limited distance. The forward mounting screw of the cage is of course tightened 20 up only sufficient to hold the cage close against the strip without binding the same against transverse movement.

By means of this arrangement it will be seen that any number of price cards or tags 25 12 of equal thickness may be supported by any one holder at whatever position in the length of the strip or shelf may be desired. The lower edges of the tags are similarly gripped between the lip 4 and the front edge 30 of the shelf; the gripping action being aided by the fact that the lip 4 is bent at an acute angle toward the shelf, as shown. To insert or remove any tag it is only necessary to engage the back lip 5 of the holder with the 35 fingers and pull outwardly so that the resistance of the springs is overcome and the lip 4 is moved away from the shelf so as to disengage the tags.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A card holder for use in connection with a shelf comprising a strip to extend under the shelf lengthwise thereof, an upstanding lip along the front edge of the strip adapted to overlap the front edge of the shelf, a depending lip along the back edge of the strip, compression springs extending transversely of and under the strip which at one end engage the forward side of said depending lip,

and means for engaging the opposite end of each spring to cooperate with said lip to maintain the spring under compression and in a substantially fixed position in connection with the shelf.

2. A card holder for use in connection with a shelf comprising a strip to extend under the shelf lengthwise thereof, an upstanding lip along the front edge of the strip, adapted to overlap the front edge of the shelf, a depending lip along the back edge of the strip, compression springs extending transversely of and under the strip which at one end engage the forward side of said depending lip, and means for engaging the opposite end of each spring to cooperate with the lip to maintain the spring under compression, and means for mounting said spring engaging means on the shelf and for also holding the strip against longitudinal movement without interfering with limited transverse movement thereof.

3. A card holder for use in connection with a shelf comprising a strip to extend under the shelf lengthwise thereof, an upstanding lip along the front edge of the strip adapted to overlap the front edge of the shelf, a depending lip along the back edge of the strip, compression springs extending transversely of and under the strip which at one end engage the forward side of said depending lip, cages enclosing the springs and engaging the ends of the same opposite to the lip to cooperate with the lip to hold the springs under compression, said cages extending back of the strip and the depending lip to rest on the adjacent portion of the shelf, and means to secure the back portions of the cages to the shelf.

4. A card holder for use in connection with a shelf comprising a strip to extend under the shelf lengthwise thereof, an upstanding lip along the front edge of the strip adapted to overlap the front edge of the shelf, a depending lip along the back edge of the strip, compression springs extending transversely of and under the strip which at one end engage the forward side of said depending lip, means for engaging the opposite end of each spring to cooperate with the lip and maintain said spring under compression, and means for mounting said spring engaging means on the shelf at selectively different locations along the strip.

5. A card holder for use in connection with a shelf comprising a strip to extend under the shelf lengthwise thereof, an upstanding lip along the front edge of the strip adapted to overlap the front edge of the shelf, a depending lip along the back edge of the strip, compression springs extending transversely of and under the strip which at one end engage the forward side of said depending lip, cages enclosing the springs and engaging the ends of the same opposite to the lip to co-
